(57) **CLAIM**

The ornamental design for the stadium chair, as shown and described.

DESCRIPTION

FIG. 1 is a front left perspective view of a first embodiment of a stadium chair in a closed position, with the dashed line indicating a boundary to claimed subject matter, and dash-dot-dash line indicated disclaimed subject matter.

FIG. 2 is a bottom left perspective view of the first embodiment of the stadium chair in a closed position, with the dashed line indicating a boundary to claimed subject matter, and dash-dot-dash line indicated disclaimed subject matter.

FIG. 3 is a top view of the first embodiment of the stadium chair in a closed position, with dash-dot-dash line indicated disclaimed subject matter.

FIG. 4 is a bottom view of the first embodiment of the stadium chair in a closed position, with the dashed line indicating a boundary to claimed subject matter, and dash-dot-dash line indicated disclaimed subject matter.

FIG. 5 is a left view of the first embodiment of the stadium chair in a closed position, with the dashed line indicating a boundary to claimed subject matter, and dash-dot-dash line indicated disclaimed subject matter.

FIG. 6 is a right view of the first embodiment of the stadium chair in a closed position, with the dashed line indicating a boundary to claimed subject matter, and dash-dot-dash line indicated disclaimed subject matter.

FIG. 7 is a front view of the first embodiment of the stadium chair in a closed position, with the dashed line indicating a boundary to claimed subject matter, and dash-dot-dash line indicated disclaimed subject matter.

FIG. 8 is a back view of the first embodiment of the stadium chair in a closed position, with the dashed line indicating a boundary to claimed subject matter, and dash-dot-dash line indicated disclaimed subject matter.

FIG. 9 is a front left perspective view of a first embodiment of a stadium chair in an open position, with the dashed line indicating a boundary to claimed subject matter, and dash-dot-dash line indicated disclaimed subject matter.

FIG. 10 is a top view of the first embodiment of the stadium chair in an open position, with the dashed line indicating a boundary to claimed subject matter, with dash-dot-dash line indicated disclaimed subject matter.

FIG. 11 is a bottom view of the first embodiment of the stadium chair in an open position, with the dashed line indicating a boundary to claimed subject matter, and dash-dot-dash line indicated disclaimed subject matter.

FIG. 12 is a left view of the first embodiment of the stadium chair in an open position, with the dashed line indicating a boundary to claimed subject matter, and dash-dot-dash line indicated disclaimed subject matter.

FIG. 13 is a right view of the first embodiment of the stadium chair in an open position, with the dashed line indicating a boundary to claimed subject matter, and dash-dot-dash line indicated disclaimed subject matter.

FIG. 14 is a front view of the first embodiment of the stadium chair in an open position, with the dashed line indicating a boundary to claimed subject matter, and dash-dot-dash line indicated disclaimed subject matter.

FIG. 15 is a back view of the first embodiment of the stadium chair in an open position, with the dashed line indicating a boundary to claimed subject matter, and dash-dot-dash line indicated disclaimed subject matter.

FIG. 16 is a front left perspective view of a second embodiment of a stadium chair in an open position, with the dashed line indicating a boundary to claimed subject matter, and dash-dot-dot line indicated disclaimed subject matter.

FIG. 17 is a top view of the second embodiment of the stadium chair in an open position, with the dashed line indicating a boundary to claimed subject matter, with dash-dot-dash line indicated disclaimed subject matter.

FIG. 18 is a bottom view of the second embodiment of the stadium chair in an open position, with the dashed line indicating a boundary to claimed subject matter, and dash-dot-dash line indicated disclaimed subject matter.

FIG. 19 is a left view of the second embodiment of the

FIG. 19. A back view of the second embodiment of the stadium chair in an open position, with the dashed line indicating a boundary to claimed subject matter, and dash-dot-dash line indicated disclaimed subject matter.

FIG. 20 is a right view of the second embodiment of the stadium chair in an open position, with the dashed line indicating a boundary to claimed subject matter, and dash-dot-dash line indicated disclaimed subject matter.

FIG. 21 is a front view of the second embodiment of the stadium chair in an open position, with the dashed line indicating a boundary to claimed subject matter, and dash-dot-dash line indicated disclaimed subject matter.

FIG. 22 is a back view of the second embodiment of the stadium chair in a open position, with the dashed line indicating a boundary to claimed subject matter, and dash-dot-dash line indicated disclaimed subject matter.

FIG. 23 is a front left perspective view of a third embodiment of a stadium chair in an open position, with the dashed line indicating a boundary to claimed subject matter, and dash-dot-dot line indicated disclaimed subject matter.

FIG. 24 is a top view of the third embodiment of the stadium chair in an open position, with the dashed line indicating a boundary to claimed subject matter, with dash-dot-dash line indicated disclaimed subject matter.

FIG. 25 is a bottom view of the third embodiment of the stadium chair in an open position, with the dashed line indicating a boundary to claimed subject matter, and dash-dot-dash line indicated disclaimed subject matter.

FIG. 26 is a left view of the third embodiment of the stadium chair in a open position, with the dashed line indicating a boundary to claimed subject matter, and dash-dot-dot line indicated disclaimed subject matter.

FIG. 27 is a right view of the third embodiment of the stadium chair in a open position, with the dashed line indicating a boundary to claimed subject matter, and dash-dot-dot line indicated disclaimed subject matter.

FIG. 28 is a front view of the third embodiment of the stadium chair in an open position, with the dashed line indicating a boundary to claimed subject matter, and dash-dot-dash line indicated disclaimed subject matter; and,

FIG. 29 is a back view of the third embodiment of the stadium chair in a open position, with the dashed line indicating a boundary to claimed subject matter, and dash-dot-dash line indicated disclaimed subject matter.
